UNITED STATES PATENT OFFICE.

FREDERICK A. METZ, OF MEADVILLE, PENNSYLVANIA.

TRAIN-ORDER DELIVERY.

1,333,435.

Specification of Letters Patent.

Patented Mar. 9, 1920.

Application filed August 4, 1919. Serial No. 315,194.

To all whom it may concern:

Be it known that I, FREDERICK A. METZ, a citizen of the United States, residing at Meadville, in the county of Crawford and 5 State of Pennsylvania, have invented new and useful Improvements in Train-Order Deliverers, of which the following is a specification.

My present invention pertains to train- 10 order deliverers and it contemplates the provision of a device whereby orders may be quickly and safely delivered to a train crew by a despatcher and this with but a minimum of effort on the part of crew and des- 15 patcher and with but a small amount of wear on the device as a whole.

The invention also contemplates the provision of a train order deliverer that is light 20 in weight, and has no stationary handle and because of these facts the hoop of the device may be easily caught by a passing trainman and thrown off at the succeeding station without injury to the hoop and furthermore 25 said hoop may be carried by the train crew to the succeeding station in a small space which is not the case with devices at present in use having the handle and hoop permanently attached. The hoops of the device may also 30 be manufactured and sold as a separate part of the device and hence greatly decrease the upkeep of the form of equipment to a railroad.

Other advantageous characteristics and 35 features of the invention will be fully understood from the following description and claims when the same are read in connection with the drawings, accompanying and forming part of this specification, in which:

Figure 1 is a front elevation of my novel 40 train order deliverer.

Fig. 2 is a section taken through the longitudinal center of the device.

Fig. 3 is a view similar to Fig. 2 with the 45 handle of the device removed from the hoop, and illustrating in section the clip I employ to retain orders on the hoop and the manner of fastening the hoop ends together.

Fig. 4 illustrates the novel clip that assists 50 in holding the hoop on the handle and also showing the stamped metal pieces forming a Y in which the hoop rests and which reinforce the handle of the device.

Fig. 5 illustrates the L-shaped plate by which the hoop ends are assisted in being held together. 55

Fig. 6 is a detail of one portion of the hoop holding and reinforcing plates, and,

Fig. 7 is a detail view of the clip or spring that removably retains the hoop on the handle. 60

Similar numerals of reference designate corresponding parts in all of the views of the drawings.

As will be readily appreciated from the drawings, the hoop 1 is at once detachable 65 from the handle 2, and said hoop is constructed from one single piece of suitable straight grain green timber and bent to form the hoop having its ends form approximately a 90 degree angle. 70

As clearly appears in Fig. 3, the ends of the hoop 1 are fastened by a small nail 3 and in order to more securely hold and reinforce said ends, I provide an L-shaped metal strap 4 that is nailed or otherwise secured as indicated by 5 over the joint of the hoop ends, and hence a strong connection of the hoop ends is assured and at the same time the ends are protected against injury when contacting with the ground. 75

After the hoop has been completed as above set forth, I attach on the inner side thereof a message clip comprising the leaves 6 and 7 formed of spring steel. The leaf 6 is first attached to the hoop by one rivet 8 85 placed in the first hole of said spring and then the outer supporting leaf is secured to the hoop by the rivet 9 which passes through the first hole of said supporting leaf and second hole of the first named leaf. The 90 rivet 10 is then driven through the last hole of the supporting leaf and then passed through a hole in the L-shaped strap 4 and from this it follows that the several leaves 6 and 7 will be prevented from turning about 95 on the hoop 1.

As clearly appears by reference to the drawings, the handle 2 is reinforced by the clips 11 and 12; said clips being of semi-circular form and secured at their lower ends 100 to said handle by rivets 13 and at their upper ends said clips diverge into Y-shaped portions 14 and 15 into which the hoop-ends are placed.

When the clips 11 and 12 have been secured on the handle, I then fasten in the head of the handle by means of a flat headed screw 16, the spring 17; which latter is prevented from working sidewise because of the construction of the sides of the clips 11 and 12.

Because of the provision and construction of the clips 11 and 12, the Y-shaped stamping produced thereby forms a pocket to hold the hoop in position on the staff or handle and through the provision of the spring 17 in the pocket the hoop will be retained in said Y shaped pocket.

In the practical use of my novel device a message is placed under the clip 6 and the hoop forced down on the handle 2, the lower ends of the hoop being engaged by the arms 14 and 15 of the clips 11 and 12 and retained on the handle by the spring 17. The despatcher then stands at a safe distance from a moving train and the engineer or other member of the train crew passes one arm through the hoop and because of the movement of the train, the hoop will be immediately detached from the handle. The hoop may then be "thrown off" at the succeeding station and hence the hoop may be sold and manufactured for sale as a separate device from the handle. The handle being retained by the despatcher, only one handle may be provided for each station, but where the handle is permanently attached as in the case of devices in present use, it is necessary for the railroads to provide each trowerman or despatcher with the completed device, which is taken away each time by a trainman and it is very unhandy for him to find a place to store the device until the next station is reached, especially when the handle is exceptionally long as required by certain railroads. Moreover where the handle is permanently attached there is increased danger of not only breaking the hoop, but also the handle when the device is thrown from a train.

It will be readily appreciated that a hoop formed of a flat piece of material is advantageous over the round piece of material for the reason that in bending, breakage of material is practically eliminated and more hoops of flat construction can be produced from a given amount of timber than round ones. Moreover my novel hoop eliminates the necessity for skilled labor in its production as it is not necessary to turn the wood through a turning machine.

It will further be noted that all of the parts of my novel device may be readily and easily produced and replaced and hence when a certain part becomes worn or broken,

it will not be necessary to discard the entire device.

Having described my invention, what I claim and desire to secure by Letters-Pat- 65 ent, is:

1. In a train order delivering device, the combination of a handle, clips secured to the upper end thereof, a spring arranged in the clips and secured on the handle, a hoop 70 having its meeting ends arranged at approximately an angle of 90 degrees, a reinforcing plate secured on the meeting ends of the hoop and a clip secured on the hoop.

2. In train order delivering means, the 75 combination of a hoop, formed of flat bendable suitable material, an L-shaped plate riveted to the meeting ends of the hoop, a message clip comprising two leaves one secured beneath the other, the first of which 80 having its outer end abutting the inner face of the second leaf, a handle having a clip formed of two semi-circular plates having diverging upper ends whereby a Y is formed, said diverging ends having a seat that receives the hoop, and a spring secured in the head of the handle and constructed and arranged to rest in the base of the Y formed by the clip and retain the hoop in movable manner on the handle. 90

3. In a device for the purpose set forth, the combination of a hoop formed of a single piece of flat bendable timber, and being square in cross-section, a message clip formed on the hoop, an L-shaped plate secured to the connecting ends of the hoop, a rivet passing through one opening of the clip and also through one opening of the plate, a staff having a reinforcing plate constructed and arranged to form a Y for receiving the ends of the hoop and means for removably securing the hoop in said Y. 95

4. In a train order delivering device, the combination of a somewhat circular hoop, having its ends connecting at an angle of 105 approximately 90 degrees, means for securely retaining the ends together, a message holding device arranged on the hoop, and a removable handle having a reinforcing plate formed by stamping a piece of 110 metal so as to embrace the handle at its lower end and terminating at its upper end in substantially a Y for reception of the ends of the hoop, and means for removably securing the hoop in the Y of the handle. 115

In testimony whereof I have hereunto set my hand in presence of two subscribing witnesses.

FREDERICK A. METZ.
